UNITED STATES PATENT OFFICE

JAMES W. BRYCE, OF BLOOMFIELD, NEW JERSEY, ASSIGNOR TO INTERNATIONAL TIME RECORDING COMPANY OF NEW YORK, OF NEW YORK, N. Y., A CORPORATION OF NEW YORK

PRINTING PAY ROLL CLOCK

Application filed May 26, 1930. Serial No. 455,661.

The present invention relates to time recorders in general and in particular to that class of recorder in which each employee records his arrival or departure upon an individual card.

It is common practice in large establishments to provide a time recorder for each group of about 150 or even more employees, each having an individual time card bearing a number identifying the employee who daily records his arrivals and departures on the card assigned to him. The time recorder is commonly constructed so that the time is recorded in a distinctive color such as red during the regular hours of labor but in a less distinctive color such as blue at all other times so that the time recorded when an employee is tardy or leaves before the usual closing hour will be distinctively displayed in a color contrasting to the other entries on the time card. Space is provided on the card so that it may be used to record the employee's arrivals and departures for the full weekly or bi-monthly payroll period, the cards being collected at the end of each payroll period and replaced with new ones.

It is usually found necessary, in order to ensure the prompt making up of the payroll, to have a clerk make a daily inspection of all time cards in each department in order to determine the names or numbers of employees who are tardy, leave before the usual closing hour, or absent. It would be possible, of course, to wait until all of the time cards have been collected before ascertaining this information but it considerably delays the making up of the payroll all for the sake of a small number of late arrivals or irregulars. It has been found from experience that the number of irregular employees is from 2% to 4% of the total, therefore, it will be apparent that only a few of the time cards in each department will show an irregularity such as a late arrival, nevertheless, all of the cards must be scanned to determine the few irregulars.

In a large business organization it requires a considerable part of the time of one or more clerks to make the daily inspection of time cards in all departments, particularly

in large factories which may be spread over a large area of land.

It is the primary object of the present invention to eliminate the necessity for such a daily inspection of time cards by providing each time recorder with additional recording means cooperating with and mechanically connected to the time recorder whereby all irregular arrivals or departures are caused to be recorded upon a record strip simultaneously with the recording of the time in the regular time card, the number of the employee recording the irregular time being recorded adjacent to the time printed upon the record strip.

A further object is to provide interlocking mechanism which locks the time recorder during the normal working periods and compels the employee to insert a special key bearing his number in the time recorder before the time of arrival or departure can be recorded in the usual way.

Other objects and advantages of the present invention will become apparent or will be pointed out further hereinafter in the following specification and claims and in the accompanying drawings, which, by way of illustration, show what at present is considered to be a preferred embodiment of the invention.

In the drawings:

Fig. 1 is a vertical sectional elevation showing a time recorder embodying the present invention, certain parts of the time recorder, not essential to an understanding of the present invention, having been omitted.

Fig. 2 is a vertical side elevation of the time recorder.

Fig. 3 is a vertical side elevation of the operating handle of the time recorder and illustrates certain of the interlocking connections.

Fig. 4 is a front elevation of the key controlled interlocking mechanism and illustrates the connections to the printing hammer for printing on the record strip.

Fig. 5 is a detail view of a key adapted for use with the present invention.

Fig. 6 is a view of a fragment of the record strip.

Fig. 7 is a detail view of the mechanism for feeding the record strip after each printing operation.

The time recorder is supported upon a base 10 contained within a casing 11 and is provided with an operating handle 12 adapted to be depressed to effect printing of the time upon the time card. The magnet 13 is arranged to receive regular electrical impulses from a master clock thereby advancing the hands of clock 14 and also minutes type wheel 15 in a well known manner. The type wheel 15, the hour type wheel 16, and the day type wheel 17 are adapted to print the time upon the time card in a well known manner. The minutes type wheel 15 is geared to drive a program wheel 18 which rotates once in twenty-four hours and is also geared to another minutes wheel 19 through suitable gearing connected with a vertical shaft 20. The minutes wheel 19 is carried upon a shaft 21 carried by the plates 22 supporting the record strip printing mechanism, and has associated therewith hour type wheel 23. The plates 22 are supported from the underside of base 10 by means of posts 24 and are spaced from each other by cross rods 25. A suitable casing 26, provided with a transparent window 27 for viewing the record strip 28, serves to enclose the entire mechanism comprising the record strip printer.

The mechanism for printing on the record strip 28 is a modification of the construction shown in the patent to Willard L. Bundy, No. 553,804, granted January 28, 1896, and includes a paper strip supply roll 29 contained in a casing 30, the record strip 28 passing from the roll 29 over lower cross rods 25, between the hammer 31 and the type wheels 19, 23, between feed rollers 32 and 33, and thence over a cross rod 34, from which the strip hangs just behind the window 27, through which the printing on the strip is clearly visible.

The hammer is pivoted at 35 to a member 36 which is fast to the cross shaft 37, journaled between the plates 22. An arm 38, fast to shaft 37, is connected by means of a link 39 to a member 40 fixed upon a shaft 41. The member 40 has pivoted to its upper end a pawl 42 adapted to cooperate with one of the wards 43 of a key 44 which may be inserted in a key hole 45 in the casing 26. The key 44, in addition to the ward 43 has a ward 46 bearing type characters 47 and is substantially identical in construction to the key shown in the cited patent. The member 40, its pawl 42, the hammer 31, and the connections therebetween are fully shown and described in the cited patent to which reference may be made for a more detailed description of the construction. It will be sufficient to mention that the member 40 normally occupies the position shown in Fig. 1 and is rocked to the position shown in Fig. 4 whenever the

key 44 is inserted in the keyhole 45 and turned 90°. Turning of the key 44 in this manner rocks the hammer 31 into position to be latched by a plate 48 carried by arms 49 integral with said plate and journaled upon a shaft 50 supported by the plates 22.

A link 51, pivoted to one of the arms 49, is also pivoted to bail 52 having an upwardly extending arm 53 connected by means of a slotted link 54 to a member 55 secured to the shaft 56 to which is secured the main printing hammer 57 for printing upon the time card. The handle 12 is loosely pivoted upon the shaft 56 and is connected to the hammer 57 by means of a latch 58 adapted to release the hammer at or near the limit of the downward stroke of the handle.

It will be clear, therefore, that a depression of the handle 12 will release the hammers 57 and 31 practically simultaneously owing to the taking up of the slack in the slotted link 54 and subsequent raising of the plate 48 to release the hammer 31, thereby effecting printing of the time upon both the time card and the record strip 28. Printing upon the record strip 28 can only be effected when a key has been inserted and turned 90° as at other times the hammer 31 would not be latched preparatory to printing.

It is desirable that printing on the time card be prevented during the usual hours of labor unless a key 44 has been previously inserted in the keyhole 45 and turned so as to compel each late arriving or early departing employee to properly record his arrival or departure on the record strip. During normal working hours the handle 12 is locked against depression by means of a locking pawl 59 pivoted at its mid-point to the main frame of the time recorder. The pawl 59, Fig. 1, during working hours, engages a shoulder 60 formed in the member 55 and prevents the handle 12 and shaft 56 from being rocked to effect recording of the time on the time card.

The locking pawl 59 has pivoted to its lower end a lever having arms 61 and 62, the arm 61 being connected by means of a link 63 to a member 64 pivoted at 65 upon a plate 66. The member 64 is raised by means of the plate 66 once each time the printing handle 12 is depressed, the plate 66 being fast to a shaft 67 which is rocked counterclockwise, Fig. 2, by means of an arm 68 fast to the shaft 67 and connected by a link to a similar arm journaled upon shaft 56 and moving in unison with the handle 12. When the member 64 is in the position shown in Fig. 2, the handle 12 is locked against operation; when rocked to the right in that figure the pawl 59 is rocked counterclockwise out of the path of the shoulder 60. The arm 62 is held in a horizontal position under normal conditions by a link 69 connected to a bail 70 pivoted on a stub shaft 71 carried by the base 10 and connected to mechanism to be de-

70

scribed later so that when the link 63 is shifted from left to right, Fig. 2, by the rocking of member 64 the pawl 59 will be rocked out of the path of the shoulder 60.

5 The member 64 forms part of the ribbon shifting mechanism and is provided with shoulders 72 and 73 adapted to engage pins 74 and 75 on the ends of an arm pivoted at 76 to the machine frame. A link 77 pivoted 10 to the pin 74 is also pivoted to an arm 78 fast on shaft 79, having secured thereto arms 80 which operate to raise or lower shafts 81 supporting the spools for the two color inking ribbon 82. Thus blue or upper half of the 15 ribbon 82 is shown at the printing line in Fig. 2 and when in this position the operating handle 12 is ordinarily unlocked, however, the ribbon has been printing blue and the member 64 has been shifted to the left 20 by means to be described later herein to position the shoulder 72 under the pin 74.

The next time the operating handle 12 is depressed the member 64 will be raised by the counterclockwise rocking of plate 66 25 thereby bringing the shoulder 72 into engagement with the pin 74, rocking the arm bearing pins 74, 75 clockwise and drawing the link 77 upwardly. The raising of link 77 rocks the arms 78, 79 clockwise and raises the ribbon spool shafts 81 to bring the red portion 30 of the ribbon 82 into the printing line so that the time will be recorded in red on the time card when the hammer 57 is released near the end of the downward stroke of the 35 handle 12.

Before the foregoing operation can take place the locking pawl 59 must be removed from beneath the shoulder 60, this operation being accomplished in the following manner 40 when the employee's individual key 44 is inserted and turned 90° clockwise to the position shown in Fig. 4. A link 83 connects one arm of the bail 70 with the end of a member 84 pivoted to one of the frames 22 at 45 85 and having a projection 86 cooperating with the ward 43 of key 44. When the key 44 is turned to bring the type 47 into alignment with the type characters on the printing wheels 19, 23 the ward 43 will engage 50 the projection 86 and rock the member 84 clockwise a sufficient amount to draw down the links 83, 69 thereby depressing arm 62 of the lever 61, 62 which will rock clockwise about the pivot point of link 63 and arm 61 55 as a center. The tail of pawl 59 and the arm 61 of the lever 61, 62, when in the position shown in Figure 2, act like a straightened toggle joint connected between the left end of the link 63 and the fixed pivot of pawl 59. 60 The member 64 is held rigidly in one or the other of its shifted positions by the pin 110 in member 109, which is operated by the star wheel 111, so that the pivotal connection between the link 63 and member 64 remains 65 fixed when the member 64 is in the position

shown in Figure 2. It will be clear that depression of arm 62 will rock the lever 61, 62 in a clockwise direction to break the toggle joint, rock link 63 slightly clockwise about its pivotal connection to member 64, and 70 rock the pawl 59 counterclockwise until the upper end of said pawl clears the shoulder 60 as shown in Fig. 3 thereby permitting a depression of lever 12. As stated hereinbefore, depression of handle 12 effects printing upon 75 both the time card and the record strip 28 since the turning of key 44 in the manner described also cocks and latches the hammer 31 ready to be released near the end of the depression of handle 12.

Pivoted to the member 84 is a link 87, connected by means of a pin and slot connection to an arm 88 secured to shaft 37. As the hammer 31 moves counterclockwise, Fig. 4, to strike the type at the printing line, the slack 85 in link 87 will be taken up and prevent the member 36 from moving further clockwise just before the hammer strikes. The hammer 31, being pivoted at 35 and normally restrained by a spring 89, will continue its 90 motion owing to its momentum and strike the type percussively and eventually will be retracted slightly in a well known manner by the spring 89. The hammer 31 is latched by the key 44 against the tension of a spring 90 95 interposed between the free ends of a pin carried by the shaft 37 and a pin fast on one of the cross rods 25. The spring 90 also ensures that the member 84 will be restored to its normal position when the key 44 is removed, the slotted connection between link 100 87 and arm 88 being proportioned to cause the spring 90 to rock members 84 and 40 a slight amount counterclockwise when the key 44 is removed. Any desired mechanism may be provided to prevent the key 44 from being withdrawn without printing and also to hold it steady when the hammer 31 strikes the type, such a mechanism being shown in the 105 patent cited herein.

A suitable inking ribbon 91 passes between the type wheels 19, 23 and the paper strip 28 and is wound upon spools 92 carried by the frames 22. Any desired ribbon feeding mechanism may be used to advance the ribbon so as to always present a fresh portion of ribbon. Since the ribbon mechanism forms no part of the present invention it need not be described in greater detail herein.

The paper strip 28 is advanced each time the member 40 is rocked by the turning of key 44 to latch the hammer 31 through the medium of an arm 93 fast upon the shaft 41. A link 94 connects arm 93 with an arm 95 loosely mounted on the shaft 96 carrying paper feed roller 33. A ratchet wheel 97 fast to the feed roll shaft 96 cooperates with a pawl 98 carried by the arm 95. It will be clear that the arm 95 will be drawn down by 120 125 130

the link 94 each time the shaft 37 is rocked to latch the hammer 31, thereby advancing the record strip 28 a sufficient distance. A suitable spring urged pawl 99 pivoted to the frame supporting the paper feeding mechanism serves to prevent retrograde movement of the feed rollers. The construction just described is a well known form of paper feeding mechanism and has been mentioned solely for completeness in description.

The member 64 is controlled by means of the program wheel 18 to effect shifting of the ribbon at the desired times. Suitable tripping members 100 are adjustably arranged upon the wheel 18 to become effective at predetermined times to lift an arm 101 connected by a link 102 with an arm 103, Fig. 2, pivoted at 104 to the machine frame. A spring pressed pawl 105 pivoted to the arm 103 cooperates with a toothed wheel 106 which is normally locked by a spring-urged member 107 pivoted at 108 to the machine frame. The wheel 106, when moved one tooth in a clockwise direction, rocks an arm 109 to the left or to the right, depending upon the previous position of the arm 109, and through a pin 110 therein, projecting into a slot in the upper portion of member 64, similarly rocks the member 64 to the left or right so as to position one or the other of the shoulders 72, 73 beneath the corresponding pin 74 or 75.

The wheel 106 has fast thereto a star wheel cooperating with pins 112 carried by arm 109 so that the arm will be oscillated from one side to the other each time the wheel 106 is turned one tooth clockwise.

The locking member 107 has a tooth 113 normally locking the wheel 106 and a pin 114 positioned above a bent over and inclined lug 115 formed in pawl 105. When the arm 101 is gradually raised by one of the tripping members 100 the link 102 will be raised also, rocking the arm 103 counterclockwise, Fig. 2, and moving the pawl 105 a distance of one tooth with respect to wheel 106. The lug 115 engages the pin 114 on the upward movement of the pawl 105 and cams the pawl to the left, eventually riding off the pin 114 to a position directly above the pin. The arm 101 is released after the program wheel 18 has been turned a sufficient distance by the clock and the link 102 and arm 103 are thereafter permitted to drop owing to the combined action of a spring 116 and gravity, and, as a consequence, the lug 115 will strike pin 114, camming member 107 to the left, removing tooth 113 from beneath the teeth of wheel 106 thereby unlocking the wheel, and at the same time the nose of the pawl 105 moves the wheel 106 one tooth further, pin 114 eventually dropping back into its former position above lug 115 to relock wheel 106.

As mentioned before, moving the wheel 106

a distance of one tooth will rock arm 109 to one or the other of its limiting positions thereby positioning the ribbon shifting member 64 to effect shifting of the ribbon so as to bring either the blue or the red portion of the ribbon to the printing line. 70

The tripping members 100 are positioned upon the program wheel 18 so as to become effective at predetermined times to shift the ribbon in the manner just described. Thus, if the hours of labor are 8:00 a. m. to 12:00 75

a. and 1:00 p. m. to 5:00 p. m., the tripping members will be set to shift the ribbon 28 from blue to red at 8:00 a. m. and 1:00 p. m. and from red to blue at 12:00 a. m. and 5:00 80 p. m. so that the time will be printed in red during the hours of labor. Any workman or employee arriving or leaving during these hours cannot operate the time recorder to print on his time record until he has inserted his individual key 44 and turned it 90° as described thereby unlocking the time recorder and permitting the usual operation. The handle 12 will be unlocked each time the ribbon is shifted from red to blue so that it 95 will be unnecessary for the employee to insert his key, therefore the hammer 31 will not be latched and no printing will be effected on the record strip 28 during periods between the prescribed hours of labor. It will be seen 99 from the foregoing that the figures printed on the record strip will represent all irregular arrivals or departures. Each day the department clerk or foreman can remove the portion of the record strip 28, make a note 100 thereon of any absentees, and then send the record strip to the payroll department. Fig. 6 shows as specimen of the record made upon the record strip, the first column indicating the employee's identification number and the second column the time of arrival or departure.

The present invention, for convenience in description and to assist in an understanding of the principles involved, has been described as embodied in a time recorder of specific construction having a particular form of operating mechanism and ribbon shifting mechanism, however, it is not desired to limit the invention to the precise embodiment shown and described as various modifications and adaptations may be made, all within the scope of the following claims. 110

I claim:

1. In a time recorder, the combination of 120 a main printing device, operating means therefor, time controlled means for locking said operating means during certain time intervals, an auxiliary printing device including retractile impression means, a latch 125 releasable by the operating means and adapted to retain the impression means in retracted position, and a manually insertible device for retracting said impression means and releasing said locking means whereby to per- 130

mit an operation of the operating means to release said latch and operate both the main printing device and the auxiliary printing device concurrently.

- 5 2. In a machine of the class described, time recording mechanism locked against operation during certain intervals of time, a supplemental time recording mechanism arranged to print during the intervals when the 70 first-named mechanism is locked, and a device insertible by the operator when the first named recording mechanism is locked against operation for releasing the latter for simultaneous operation with the supplemental recording mechanism.
- 10 3. In combination, a main operating member for effecting recording operations, time controlled means for locking said member during certain time intervals, a normally ineffective printing device including an impression member adapted when retracted and released to effect a printing impression, means 80 releasable by the main operating member for holding said impression member in retracted position, and manually insertible means operable to disable the locking means and retract the impression member whereby to permit an operation of the main operating member 85 to effect release of the impression member 90 and thereby render the printing device effective to print.
- 20 4. In a time recorder, a main printing device, means for preventing an operation of said device during certain time intervals, a normally ineffective auxiliary printing device including a retractible impression device, means releasable by an operation of the main printing device for retaining the impression device in retracted position, and a manually 100 insertible device for retracting the impression device and releasing the first named means whereby to permit an operation of the main printing device to release the retaining means and thereby effect a printing operation 105 by the auxiliary printing device.
- 25 5. In a workman's time recorder, an operating member for effecting recording operations upon an individual record card, means for preventing an operation of said member 110 during certain intervals of time, normally ineffective mechanism adapted to be operated by the operating member to record upon a separate record medium the time of arrivals or departures of workmen during the intervals of time when an operation of said member is prevented, and a device individual to each workman operable to disable the first named means and render said recording mechanism effective for operation by the operating member.
- 30 6. In a time recorder, a printing device including a retractible impression device, means for holding said impression device in retracted position, and a manual member for releasing the holding means; mechanism for 115 locking the manual member against operation during certain intervals of time, and a device insertible by the operator during such time intervals for retracting the impression device and disabling the locking mechanism 120 whereby an operation of the manual member releases the impression member holding means to effect an imprint.
- 35 7. In a time recorder the combination of a main recording mechanism, manual means for operating said main recording mechanism, an auxiliary recording mechanism adapted to be connected to the manual means for operation by the latter, means for rendering the manual means ineffective during certain time intervals, and a device operable by the operator to disable the preventing means and operatively connect the auxiliary recording mechanism to the manual means for operation by the latter concurrently with an 125 operation of the main recording mechanism.
- 40 8. In combination, printing mechanism operable to record the time of a workman upon an individual record card, time controlled mechanism for locking the first named printing mechanism against operation during certain time intervals, a second printing mechanism adapted to record irregular arrivals or departures of workmen during the intervals when the first named printing 130 mechanism is locked against operation and adapted to be operatively connected to the first named printing mechanism for simultaneous operation with the latter, and a device insertible by a workman arriving or leaving during the aforesaid time intervals for disabling the locking mechanism and operatively connecting the second printing mechanism to the first named printing mechanism for concurrent operation with the latter.
- 45 9. In combination, printing mechanism operable to record the time of a workman upon an individual record card, time controlled mechanism for locking the first named printing mechanism against operation during certain time intervals, a second printing mechanism adapted to record irregular arrivals or departures of workmen during the intervals when the first named printing mechanism is locked against operation and adapted to be operatively connected to the first named printing mechanism for simultaneous operation with the latter, and a device insertible by a workman arriving or leaving during the aforesaid time intervals for disabling the locking mechanism and operatively connecting the second printing mechanism to the first named printing mechanism for concurrent operation with the latter, said insertible device being provided with means 135 for recording adjacent the time of an irregular arrival or departure printed by the second printing device an identifying character representing the workman inserting the insertible device.

10. In combination, time recording mechanism operable to print both regular and irregular registrations, an auxiliary time recording mechanism arranged to record only irregular registrations and adapted to be operatively connected to the first-named recording mechanism when the latter is operated to print an irregular registration, and a manually operable device for insertion by the operator during the times when the first-named recording mechanism is printing irregular registrations for establishing an operative connection between both recording mechanisms whereby an operation of the first-named mechanism also effects a registration by the auxiliary time recording mechanism. 15
11. In combination, time recording mechanism operable to print both regular and irregular registrations, an auxiliary time recording mechanism arranged to record only irregular registrations and adapted to be operatively connected to the first-named recording mechanism when the latter is operated to print an irregular registration, and a manually operable device for insertion by the operator during the times when the first-named recording mechanism is printing irregular registrations for establishing an operative connection between both recording mechanisms whereby an operation of the first-named mechanism also effects a registration by the auxiliary time recording mechanism, said manually operable device having a part co-operating with the auxiliary recording mechanism to record a workman's identifying character adjacent the time registered by the auxiliary recording mechanism. 20
12. In combination, a main recorder, an auxiliary recorder, time controlled means for locking the main recorder against operation during certain periods and means controlled by a part of the auxiliary recorder for disabling the locking means rendering the main recorder operative during said periods. 25
13. In a workman's time recorder, a main recording device for recording both regular and irregular arrivals or departures of workmen, an auxiliary recording device adapted to be operatively connected to the main recording device for operation by the latter and arranged to record only irregular arrivals or departures of said workmen, and a device insertible by a workman and individual to the latter for operatively connecting the auxiliary recording device to the main recording device for operation by the latter. 30
14. In a workman's time recording device, a main recorder, a normally ineffective auxiliary recorder associated with the main recorder and adapted to be operated by the latter, time controlled means for preventing operation of the main recorder during predetermined periods, and a device for disabling the preventing means and rendering the aux- 35
- iliary recorder effective for operation by the main recorder. 40
15. A workman's time recorder comprising mechanism for making both regular and irregular registrations on a single record medium, auxiliary mechanism for making only irregular registrations on a separate record medium, said auxiliary mechanism being adapted to be operatively connected to the first named recording mechanism for conjoint operation by the latter, and a device insertible by an individual workman for operatively connecting the auxiliary mechanism to the first named mechanism for operation by the latter, said device having a part co-operating with the auxiliary recording mechanism to register adjacent the irregular time registration of said workman a character identifying the workman with the irregular time registered by the auxiliary mechanism. 45
